ONE-REVOLUTION LATCH-OPERATED
CLUTCH

Cecil P. Love, Rock Island, Ill.

Application July 14, 1945, Serial No. 605,172

6 Claims. (Cl. 192—26)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a firing mechanism for a gun and more particularly to control means for operating the actuator for the gun firing mechanism.

The invention is particularly adapted to and provides improvements in gun firing mechanisms of the type characterized by the provision of an actuator which is continuously powered and selectively connectible to the firing mechanism to actuate the latter for firing the weapon. One such arrangement of this type consists of an actuator comprising a constantly rotating driving part, an intermittently rotatable driven part, a clutch member for connecting the two parts together in driving relation for predetermined cycles of revolution, and means connecting the intermittently rotatable part to the firing mechanism so that the latter is actuated during the intervals or cycles in which the intermittently rotatable part is connected to the driving part.

It is desirable in gun firing systems of the type referred to that the actuator be permitted to operate the firing mechanism only during the desired cycles. It is accordingly desirable that means be provided for disconnecting the driving and driven parts at the end of each cycle. However, in cases where the firing system includes an electrical firing circuit, or other means connected to a source of power, it often happens that the operator fails to break the firing circuit, with the result that the driving and driven parts of the actuator remain connected.

It is accordingly a principal object of the invention to provide control means for a firing system of the type referred to wherein said control means is operable to disconnect, or render inoperative, the actuator parts at the end of each cycle of operation.

It is also a principal object of the invention to provide a control means in which cyclic disconnection of the parts occurs automatically even though release operation of the control means is prevented or resisted by the operator or otherwise.

An important object of the invention is to adapt the control means to a firing system including an electrical firing circuit.

Another object of the invention is to provide a control means including primary means to release and engage the clutch member of the actuator and a secondary means adapted to engage

2

the clutch means in the event that the primary means fails to engage the clutch means at the end of the cycle of the latter.

The invention has for another object the provision of control means that may be readily adapted to firing actuators of existing types.

And still another object of the invention is to provide a control means in the form of a single actuatable member provided with suitable portions adapted to carry out the functions of the above mentioned primary and secondary engaging means.

A complete understanding of the construction and operation of a preferred embodiment of the invention may be had from the following detailed description and accompanying sheet of drawings in which:

Fig. 1 is a longitudinal sectional view through one form of firing actuator showing the relationship between the control means and the actuator parts;

Fig. 2 is a transverse sectional view through the actuator as viewed along the line 2—2 of Fig. 1;

Fig. 3 is a fragmentary, longitudinal sectional view taken along the line 3—3 of Fig. 2;

Fig. 4 is an end elevational view of the actuator; and

Fig. 5 is an enlarged perspective view showing the construction of the control member.

The actuator chosen for the purposes of illustration comprises a base 10 having an upstanding vertical wall 11 to which is securely attached a source of power such as an electric motor 12. The base 10 is adapted to be secured in any suitable manner to the supporting structure of the gun in which the actuator and firing mechanism are to be installed.

The base 10 includes an upstanding bracket 13 in which is carried a suitable antifriction bearing, herein shown as comprising a pair of ball bearings 13a spaced apart axially by an apertured sleeve 13b that also forms a common inner race for both bearings. This bearing journals a sleeve 14 of a constantly rotating part designated generally by the numeral 15. This part further includes a drum 16 preferably formed integrally with the sleeve 14. The drum includes an internal ring gear 17 meshing with and driven by a pinion 18 which is in turn driven by the electric motor 12. The sleeve 14 is provided in its interior with suitable antifriction bearings, herein shown as a pair of roller bearings 14a spaced axially apart by an apertured sleeve 14b. The sleeve 14 is also apertured so that lubricant may

circulate freely throughout the bracket or housing 13. The bearings 14a journal therein an intermittently rotatable part in the form of a shaft 19 formed at its outer end with an eccentric or crank 20 and at its inner end with a second eccentric or crank 21. The eccentric 20 at the outer end of the shaft engages a slot 22 extending longitudinally in an actuator arm 23 pivoted at one end to a bracket 24 on the base 10 and connected at its other end to an actuating rod 25. As will be hereinafter described, the shaft 19 is rotated in successive cycles and by means of the eccentric 20 the actuator arm is oscillated to effect reciprocation of the actuator rod 25. This rod is connected in any suitable manner to the firing mechanism of the gun. This mechanism may be of any conventional type, although the particular type of actuator illustrated is especially adapted for the actuation of firing mechanism of the continuous-pull self-cocking type.

The eccentric 21 at the inner end of the shaft 19 has securely mounted thereon for rotation therewith a clutch arm 26 extending radially outwardly from the eccentric 21 and having at its outer end a clutch shoe 27 adapted to engage a clutch track 28 formed on the inner periphery of the drum 16 coaxially spaced from the ring gear 11. Spring means 29 operates between the shoe 27 and the arm 26 to urge the shoe 27 normally into engagement with the clutch track 28 of the drum 16. Because of the eccentric relation between the eccentric mounting 21 and the shaft 19, and because of the slight frictional drag of the track 28 on the shoe 27, the normal tendency of the clutch arm 26 is to move in the direction of rotation of the drum 16 so that the shoe 27 engages the clutch track 28, this movement effecting a driving connection between the constantly rotating part 15 and the intermittently rotatable part or shaft 19.

In the particular arrangement of parts herein illustrated means are provided for normally maintaining the clutch arm 26 in position so that the shoe 27 cannot engage the clutch track 28. This means comprises a clutch rod or lug 30 preferably formed integrally with and extending outwardly from the clutch arm 26 and having a portion directed radially inwardly toward the eccentric 21. The means for controlling the operation of the clutch arm 26 includes means for selectively and automatically engaging and disengaging the clutch lug 30 so that the clutch arm 26 may be selectively released for engagement with the drum 16 and re-engaged for disengagement from the drum 16, thus establishing and interrupting driving connection between the constantly rotating part and the intermittently rotatable part. In the preferred form of the invention the control means takes the form of a solenoid 31 suitably connected to a source of electrical energy. The solenoid may be arranged in the firing circuit in any desirable manner. Likewise the solenoid may be replaced by equivalent operating means that may be either power or manually operable. However the principle of operation involved will be the same in any instance, as will hereinafter appear.

The solenoid includes a plunger 32 of conventional construction arranged to abut a coaxial control member 33 slidably carried by the supporting wall 11 of the base 10 and extending within the drum 16. The control member is so mounted in the supporting wall 11 that it may reciprocate but may not rotate or turn on its

axis, this result being achieved by a key (not shown). The portion of the control member adjacent the solenoid plunger 32 is provided with a washer 34 secured in place by a nut 35, and a compression spring 36 is compressible between the washer 34 and the supporting wall 11 to maintain the control member in an initial retracted position. The portion of the control member 33 within the drum 16 includes, preferably integrally therewith, a control head having a main body portion 37 and a circular shoulder 38 engageable with a boss on the supporting wall 11. As best shown in Figs. 1 and 5, the main body 37 of the control member 33 is provided with means selectively and alternately engageable with and releasable from the clutch lug or rod 30. The body portion 37 is cut out to form a first passage or groove 39 extending generally transverse to the path of reciprocation of the control member. A second passage or groove 40 is formed in the body portion at a point spaced from the first passage 39 along the path of reciprocation of the control member. The first and second passages are interconnected by a third passage or groove 41 extending generally normal to the first two passages or along the line of reciprocation of the control member. The arrangement of the passages 39, 40 and 41 is such as to provide a first means in the form of an abutment 42 arranged at one corner of the main body portion and a second means in the form of a second abutment 43 disposed diagonally across from the first abutment. The abutments on the control member are so arranged with respect to the circular path through which the clutch lug moves as to be spaced apart in the direction of rotation of the clutch lug and further spaced apart in a direction normal to the plane of rotation of the clutch lug.

In the particular type of firing arrangement illustrated the electric motor 12 is powered so as to run continuously throughout selected periods during which it is expected that the weapon will be fired. For example, during a prolonged combat period the motor 12 will be continuously running and the drum 16 will therefore be constantly rotated. When it is desired to fire the weapon, the firing circuit is closed (or the equivalent system is operated) and the solenoid 31 is energized so that the plunger 32 contacts the control member 33, moving the latter axially into the drum 16. As best shown in Fig. 1, the normal position of the parts is such that the clutch lug 30 is engaged by the first abutment 42 on the main body 37 of the control member and the clutch arm 26 and shoe 27 are held against movement into engagement with the constantly rotating drum 16. When the control member is moved inwardly by the solenoid plunger 32, the main body portion 37 of the control member moves toward the clutch lug 30 to align the lug with the first passage 39 of the control member. Thus the clutch arm 26 is released for movement so that the shoe 27 may engage the clutch track 28 in the drum 16 and the shaft 19 is rotated with the drum. This rotary motion is translated through the eccentric 20 to the actuator arm 23 and thence to the firing mechanism by means of the actuator rod 25.

It is desirable in the presently illustrated type of actuator that the intermittently rotatable part 19 be disconnected from the drum 16 after one complete revolution thereof, since movement of the parts through a cycle of one revolution is sufficient to actuate the firing mechanism. It is

therefore necessary that means be provided for disconnecting the driving relationship between the drum 16 and shaft 19 upon completion of the cycle and it is desirable that this means be automatic in operation. This function is accomplished by means of the control member 33 which is adapted to be interposed in the path of the clutch lug 30 as the clutch arm 26 nears the completion of its cycle of one revolution. In normal circumstances in the use of the present invention, the firing circuit will be broken (or the power from an equivalent source will be disconnected) and the solenoid plunger 32 will be returned, thus permitting the spring 36 to return the control member 33 to its initial position so that the clutch lug 30, when it reaches the end of its cycle of revolution, will again engage the first abutment 42 on the main body 37 of the control member. Thus the parts are conditioned for the initiation of a new cycle of revolution, which occurs when the control member 33 is again moved inwardly so that the clutch lug 30 may pass along the passage or groove 41 and out the passage 39.

However, it often occurs that through some action on the part of the operator of the weapon or through some defect in the firing control system return movement of the control member 33 may be resisted or prevented. Normally such defect or failure in the system would permit the clutch arm 26 to remain in engagement with the drum 16 and the actuator rod would continue unnecessarily to reciprocate and actuate the firing mechanism. In the present instance, this difficulty is eliminated by means of the control member comprising the body portion 37 with its interconnected grooves 39, 40 and 41 and abutments 42 and 43. In the event that the control member 43 is maintained in its release position after it has released the clutch lug 30, the body portion 37 is still capable of disengaging the clutch arm 26 after completion of one revolution thereof. This result occurs because, as the control member is moved inwardly to release the clutch lug 30 through the passage 39, the abutment 43 on the body portion 37 is simultaneously moved into the path of the clutch lug at a point just prior to completion of the cycle of revolution, whereupon, if the control member remains in this assumed position, the clutch lug 30 engages the abutment 43 and the clutch arm is disengaged from the drum. Then, if the control member is again returned to its initial position, the abutment 43 is moved out of the path of the clutch lug 30. However, this does not free the clutch lug to permit another revolution of the clutch arm 26, since the clutch lug will now engage the abutment 42. It is therefore necessary that the control member 33 be again moved to release position so that the lug 30 will be freed from the abutment 42. By means of the aforesaid arrangement it is necessary that the control member be actuated separately for each firing cycle; likewise continuous or uninterrupted actuation of the firing mechanism is precluded.

It will be seen from the foregoing description that the control means is simple and efficient in construction and operation and is admirably suited for the accomplishment of the objects set forth above. It will be understood of course that the preferred embodiment of the invention may be subject to many modifications and alterations without departing from the spirit and scope of the invention as defined in the appended claims.

I claim:

1. In an actuator for a gun firing mechanism, a driving drum, a driven shaft, base means journaling said drum and shaft for rotation about a common axis, a bearing on said shaft eccentric of said axis, a clutch unit journaled on said bearing and having a part engageable with the inner periphery of said drum, a projection on said unit offset therefrom parallel with said axis, a control element slidable on said base means parallel with said axis, said element having first and second lugs spaced parallel with said axis and also spaced circumferentially of the path of said projection to permit said projection to pass therebetween, power means operable to move said element between first and second positions wherein said lugs lie in the path of said projection respectively, said lugs overlapping in said axial direction; and actuator means connected for operation by and in response to rotation of said shaft.
2. In an actuator for a gun firing mechanism, a drum having an internal track concentric about an axis, means mounting said drum for rotation about said axis, a shaft journaled for rotation on said axis and having one end extending into said drum, an eccentric on said one end of said shaft, an arm journaled on said eccentric, a shoe on said arm adapted to engage said track, a lug on said arm, a control member slidable in a direction substantially parallel with said axis, from a first to a second position, said member when in first position being adapted to engage said lug to prevent rotation of said arm and shaft and when in said second position releasing said lug, means for so sliding said member, power means connected to rotate said drum, and actuator means connected with said shaft for actuation on rotation thereof.
3. An actuator for a gun firing mechanism comprising a base, a drum journaled on said base for rotation about an axis and having an internal track concentric of said axis, a shaft journaled on said base on said axis, said shaft having an eccentric on one end, an arm journaled upon said eccentric, a shoe pivoted upon said arm and adapted to engage said track, means urging said shoe into engagement with said track, a lug on said arm adjacent said shoe, a control member translatable on said base into and out of the path of rotation of said lug, a motor carried by said base and connected to continuously rotate said drum, actuator means connected for operation by and upon rotation of said shaft, and manually controlled power means operable to translate said member.
4. An actuator for a gun firing mechanism comprising a base adapted to be secured to a gun, a drum journaled upon said base for rotation about an axis, there being a track on said drum internally thereof and concentric of said axis, a shaft journaled on said base on said axis and having an eccentric within said drum, a clutch arm journaled on said eccentric, means on the end of said arm adapted to engage and disengage said track, a first lug on said arm extending therefrom adjacent said track parallel to said axis, a control member slidable on said base parallel with said axis, between first and second positions, said member having second and third lugs each adapted to engage said first lug when said member is in a respective one of said positions, said lugs being spaced circumferentially along the path of said first lug and axially in a direction parallel with said axis, power means connected to continuously rotate said drum, actuator means

connected for actuation by and in response to rotation of said shaft, and manually controlled means for sliding said member between said first and second positions.

5. An actuator as recited in claim 4, said second and third lugs overlapping in an axial direction whereby to prevent passage of said first lug therebetween.

6. In an actuator for a gun firing mechanism, a base adapted to be secured to a gun, a drum rotatable on said base about an axis and having a sleeve extending from one side wall concentric of said axis, a shaft journaled in said sleeve and having an eccentric on one end within said drum, an internal track on said drum concentric of said axis, a clutch arm journaled on said eccentric, a shoe movable on said arm, adapted to engage said track, a first lug on said arm projecting therefrom parallel to said axis, a control member translatable on said base parallel to said axis between a first and a second position, said member having thereon second and third lugs, each

15
10
15

adapted to lie in the path of and obstruct said first lug for a respective position of said member, said second and third lugs overlapping in a direction parallel to said axis, and also being spaced circumferentially of the path of rotation of said first lug, to permit said first lug to pass therebetween, power means to rotate said drum, manually operable control means for selectively translating said control member between said first and second positions, and actuator means driven by and in response to rotation of said shaft.
